REFRIGERATION APPARATUS

Carl Oscar Bergstrom, Hyde Park, Mass., assignor
to B. F. Sturtevant Company, Inc., Boston,
Mass.

Application September 5, 1934, Serial No. 742,754

9 Claims. (Cl. 230—190)

This invention relates to refrigeration apparatus, and relates more particularly to refrigerant compressors of a type particularly suitable for domestic refrigerators.

5 Although the refrigerant compressors used in household refrigerators have been improved greatly in the past few years, most of those generally used are still too noisy, are too complicated, and so constructed as to require frequent serv-

10 icing and replacements. Desirable features in a household compressor unit are that the driving motor should not be compelled to start under full load; that adequate and automatic lubrication be provided; that it be very quiet in opera-

15 tion; that it be suspended so as to transmit no vibrations to the cabinet within which it is suspended, and that it operate satisfactorily over a long period of time without necessity for serv-

icing.

20 According to a feature of this invention, there is mounted within the piston of a refrigerant compressor a simple spring-operated unloading device, which holds the suction valve to the compressor cylinder open until substan-

25 tial pressure has developed beyond the valve to then close same, thus permitting the driving motor to attain substantial speed before picking up its full load. It has previously been proposed to use unloading devices with com-

30 pressors, but those devices previously proposed have been much more complicated and expensive than the simple one according to this invention.

According to another feature of this invention, a muffler is provided in the cylinder head of the 35 compressor to silence the noise caused ordinarily by the pulsation in the vapor pressure.

According to another feature of this invention, lubrication difficulties are minimized by utilizing ball bearings for the main bearings, and by providing forced feed lubrication for all of the other 40 bearings with oil circulating with the vapor through the apparatus.

According to another feature of this invention, the tendency of the suction valve to stick 45 open, due to the formation of an oil film on the outlet side thereof, is eliminated by providing a spring which tends to maintain the suction valve closed, but the pressure of which is insufficient to prevent the opening of the valve during the suction stroke of the piston.

According to another feature of this invention, the compressor and driving motor are suspended from an underslung base by two simple flat springs which prevent the transmission of vi- 50

An object of the invention is to decrease the noise of operation of a refrigerant compressor.

Another object of the invention is to provide a simple, inexpensive unloading device for a refrigerant compressor.

Another object of the invention is to utilize oil carried with the refrigerant through the refrigeration cycle to lubricate bearings of the apparatus.

Another object of the invention is to provide 10 a valve structure for the refrigerant compressor, which is capable of continuous trouble-free operation.

Another object of the invention is to provide a simple spring structure for the support of and 15 the observation of any vibrations set up by the operation of refrigeration apparatus.

Another object of the invention is to provide a refrigerant compressor capable of quiet, trouble-free operation, which will operate with minimum 20 expense, maximum efficiency, and without necessity for frequent servicing.

Other objects of the invention will be apparent from the following description taken with the drawings, of which:

Fig. 1 is a plan view, looking downwardly upon 25 an assembled compressor unit according to this invention;

Fig. 2 is an end view looking towards the compressor, of Fig. 1;

Fig. 3 is an enlarged vertical sectional view 30 through the compressor and through the bearings of the motor;

Fig. 4 is a sectional view along the lines 4—4 of Fig. 3;

Fig. 5 is a sectional view along the lines 5—5 35 of Fig. 3;

Fig. 6 is a plan view looking downwardly on the muffler adapted to be mounted in the cylinder head, as shown by Fig. 5. A portion of two of 40 the muffler plates is removed to show the spacing of the openings provided for the passage of the compressed vapor;

Fig. 7 is a plan view, looking upwardly upon the outlet valve structure of Fig. 5;

Fig. 8 is a plan view looking downwardly upon 45 the outlet valve structure of Fig. 5, and

Fig. 9 is a plan view looking upwardly upon the head of the piston of Fig. 5, and illustrates the inlet valve in position within the cylinder 50 head with the plurality of openings for the passage of the vapor from the piston head.

The assembled compressor motor unit is illustrated by Figs. 1 and 2. The induction motor 10, which is preferably of the capacitor type, 55

is bolted to the compressor 11 by means of the nuts 13 screwed upon the bolts 12. The compressor 11 is supported from the base 14 by means of the single leaf spring 15, the two ends of which are attached to the upper portion of the compressor at 16, and the flattened base portion of which is attached to the base 14 by means of the nuts 17 on their associated bolts which extend into the base. The motor 10 is likewise supported from the base by means of a similar leaf spring 18, the two ends of which are rotatedly attached at the upper portion of the motor housing at 19 and the flattened base portion of which is attached to the base 14 by the two nuts 20 on their respective bolts which extend into the base.

This simple spring suspension permits the unit to float freely at its two ends and absorbs all movement of the unit, thus preventing the transmission of any vibrations to the base 14. The unit can be quickly and easily placed on or removed from its base and the supports have sufficient strength for all stresses which may be placed upon them.

25 The internal mechanism of the compressor will now be described with reference to Figs. 3 to 9, inclusive.

30 The compressor 11 is of the single stage type, having but a single piston because of the difficulties of equally loading the pistons of multi-stage units.

35 The piston 21 is adapted to be reciprocated by means of its piston rod 24, the lower end of which is rotatably mounted on the shaft 22, which, in turn, is rotatably and eccentrically mounted upon the shaft 23, which, in turn, is rotated by the armature of the electric motor. The upper end of the piston rod 24 is rotatably mounted upon the wrist pin 25 of the piston 21.

40 The suction valve mechanism is contained within the piston 21. The piston has a removable head 26 which is threaded into the upper portion of the piston with threads at 27. The upper portion of the piston is provided with a central opening 28, through which the vapor passes to be later compressed. Above and communicating with the opening 28, is the larger opening 29, over which the valve 30 seats to close off the flow of vapor. Arranged within the opening 29 and in contact with its base and with the piston 30, is the unloading spring 31, which is provided to prevent the seating of the valve 30 until sufficient pressure has developed on the output side of the valve to overcome the pressure of the spring 31, thus permitting the valve to become seated against the opposing action of the spring. This permits the motor driving the compressor to attain substantial speed before picking up the full load of compressing the refrigerant.

60 The removable head 26 of the piston is provided with a central groove 32, in which is mounted the spring 33. The upper portion of the spring 33 contacts with the upper extremity of the groove 32 and the lower portion of the spring 33 contacts with the upper surface of the valve 30. Spring 32 develops sufficient pressure to prevent the valve 30 from sticking to the lower portion of the piston head 26. Oil is carried by the vapor passing through the valve and it is difficult to prevent a thin film of oil from forming on top of valve 30 and often, when the valve was opened and came in contact with the lower portion of the piston head 26, the film of oil caused it to stick to the lower portion of the piston head,

thus causing the valve to remain open during the compression strokes. The spring 33 is incapable, however, of preventing the valve 30 from opening when it should open in its normal operation.

5 During the down stroke of the piston, the vapor passes into the cylinder through the plurality of openings 35, the circumferential arrangement of which is illustrated by Fig. 9. The vapor is then compressed during the up stroke of the piston and then passes through the central opening 36 above the head 26 of the piston and past the outlet valve 31, which is lifted up at the end of the compression stroke to permit the vapor to flow into the opening 38, which, in the ordinary 10 compressor, is the exhaust port.

Provided above the opening 38 within the end housing or cylinder head 80 of the compressor are the three muffler discs 39, 40 and 41. The discs are spaced apart by means of the washers 20 42 and 43. The lower disc 39 contains the small openings 45 which are out of alignment with openings 44, and the outer disc 41 is provided with the openings 46 which, again, are out of alignment with the openings 45 in its neighboring disc 40. In operation, the compressed vapor leaving the cylinder of the compressor, tends to expand suddenly in the greater space provided by the discharge outlet and connecting to it. This causes a pronounced noise which the muffler 30 herein described completely dissipates. This is accomplished by having the compressed vapor from the cylinder pass first through the openings 44 in the disc 39, the vapor then expanding to a degree in the space between the discs 39 and 40. 25 The vapor next passes through the openings 45 in the disc 40, and again expands in the space between the discs 40 and 41. The vapor then passes through the small openings 46 and expands into the outlet from the compressor. The 35 expansion into the outlet of the compressor thus takes place in several stages, with the result that the noise usually caused by the intermittent compressions and expansions is eliminated.

40 The compressed vapor, after passing through the final muffler openings 46, passes from the compressor through the openings 47 and 48.

45 The outlet valve 31 is normally restrained from opening, due to the pressure of the three-tongued spring members 50, which press downwardly upon its upper surface and which are formed in a disc of spring metal. Additional discs with springs 50 may be added to adjust the pressure upon the valve 31 (see Figs. 7 and 8). The spring members 50 are centered in the slots 51 of the plate 52. 55

50 The muffler and outlet valve mechanism are bolted to the upper portion of the compressor by means of the three screws 53.

55 By way of example, a refrigerant compressor according to this invention, may contain 18 ounces of methyl chloride and 8 ounces of oil. The oil is carried through the apparatus with the vapor and is used to lubricate certain of the bearings as follows:

60 The oil and vapor returning from the expansion coils enter the compressor through the inlet port 55 (Fig. 3) and then pass through the sylphon seal 56 and along the shaft 23 into the channel 57, where it provides lubrication for the contact between the members 58 and 59. The oil then passes through several radial openings 60 (only one of which is shown) into the central opening 61 of the shaft 23. Some of the oil passes out the opening 62 at the end of the shaft and some passes up through the channel 63 to 75

lubricate the bearing between shaft 23 and eccentric cylinder 22, after which the oil passes into the opening 64 in the cylinder 22 and thence through the channel 65 to lubricate the bearing 5 between the piston rod 24 and cylinder 22.

Referring now to Fig. 5, it is seen that the oil carried by the vapor into the interior of the piston 21, enters the channel 66 in the upper portion of the piston rod 24 and lubricates the bearing 10 of the wrist pin 25.

The lower portion of the piston rod 24 is provided with a scoop 67 for picking up oil from the oil sump 68 in the lower portion of the compressor. The oil level is maintained just above 15 the end of the scoop 67 and tapped plug 69 is provided at the end of the compressor to enable inspections to be made as to the oil level.

The main compressor bearing 70 and motor bearing 71 are ball bearings, the latter of which 20 may be suitably packed in grease and the former of which is lubricated by slight leakage of oil past the thin metal seals 72, which are provided to prevent the passage of any substantial amount 25 of vapor and oil under pressure through the bearing.

The shaft 23 of the unit is integral throughout the motor and compressor. This is preferred 30 because it eliminates the necessity for shaft couplings and provides stronger construction.

In operation, upon rotation of the shaft 23 by the motor, the oil and vapor within the compressor 35 is drawn by the suction action of the piston through the inlet valve 30. As previously explained, this valve remains open, due to the action of the spring 31, until sufficient pressure has developed on the output side of the valve to overcome the action of the spring 31, thus enabling the motor to develop full speed before taking up its full load.

To prevent any oil film on the upper side of the valve 30 from causing the valve to stick to the lower portion of the piston head 26, the spring 33, which tends to force the valve 30 away from the piston head, is provided.

The valve 30 is opened during its downward stroke by the action of the vacuum created above it, the outlet valve during suction being maintained, of course, closed. During the upward and compression stroke of the piston, the valve 30 is closed by the pressure developed above it. During the down stroke, valve 30 is open and the vapor drawn in through this valve passes out into the compressor cylinder through the plurality of circumferential openings 35 (Figs. 5 and 9) and 55 enters the space 36 below the outlet valve 37. The outlet valve 37 is normally maintained closed by action of the springs 50, which press downwardly upon its upper surface. During operation, the compression developed beneath the valve 37 is sufficient to overcome the action of the springs 50, causing the valve to open. The compressed gas then enters the space 38 and passes through the staggered small openings in the compressor discs 39, 40, and 41, which have previously been 60 described, which enable the compressed refrigerant to be sufficiently expanded and so gradually that the noise of discharge which occurs where no muffler is provided, is overcome. The gas then passes through the space 47 and outlet 48 into the tubing which is employed to convey the refrigerant to the condenser and the condenser and evaporator coils.

It has been found that the loss in compression and of efficiency of the unit through the use of the muffler is so slight as compared to the ad-

vantages gained through the quietness of operation, that they are immaterial. It is realized that other forms of silencers, such as a different type of muffler or acoustic filters may be substituted for the muffler illustrated, by those skilled in the art, after having had access to this disclosure.

Whereas one embodiment of the invention has been described for the purpose of illustration, it should be understood that the invention is not limited to the details described, since many modifications may be made by those skilled in the art without departing from the spirit of the invention.

What is claimed is:

1. In refrigerating apparatus, the combination 15 of a compressor cylinder, a cylinder head, a piston movable in said cylinder, a removable head for said piston, and a suction valve located within said piston adjacent said removable head, said piston having a central opening therein for the 20 intake of fluid during the suction stroke of said piston, and said piston having a plurality of circumferentially arranged openings for permitting the passage of vapor from said piston into the compression side of said cylinder during the suc- 25 tion stroke of said piston in said cylinder.

2. In refrigerating apparatus, the combination 30 of a compressor cylinder, a head through which compressed vapor is discharged, a piston movable in said cylinder for compressing the vapor, an exhaust valve between the compression side of said piston and the head of said cylinder, and means comprising a silencer between said valve and the head of said cylinder for silencing the noises of the vapor resulting from 35 the action of said piston thereon.

3. In refrigerating apparatus, the combination 40 of a compressor cylinder, a head through which compressed vapor is discharged, a piston having a compression side and a suction side movable in said cylinder for compressing the vapor, an exhaust valve between the compression side of said piston and the head of said cylinder, and means comprising a silencer between 45 said valve and the head of said cylinder for silencing the noises of the vapor resulting from the action of said piston thereon.

4. In refrigerating apparatus, the combination 50 of a compressor cylinder, a head through which compressed vapor is discharged, a piston having a compression side and a suction side 55 movable in said cylinder for indrawing and compressing the vapor, exhaust valve mechanism, muffler mechanism for muffling the noises of the vapor resulting from the action of said piston thereon, and means for securing said valve mechanism and said muffler mechanism within the compression side of said cylinder between the head thereof and the compression side of said piston.

5. In refrigerating apparatus, the combination 60 of a compressor cylinder, a head through which compressed vapor is discharged, a piston having a compression side and a suction side movable in said cylinder for indrawing and compressing the vapor, exhaust valve mechanism, muffler mechanism for muffling the noises of the vapor resulting from the action of said piston thereon, and common means for securing said valve mechanism and said muffler mechanism within the compression side of said cylinder between the head thereof and the compression side of said piston.

6. In refrigerating apparatus, the combination 70 of a compressor cylinder, a head for said 75

5 cylinder, a piston movable in said cylinder for compressing a refrigerant vapor and an exhaust valve assembly mounted between the head of said cylinder and the compression side of said piston, said assembly comprising a relatively small disc valve, a relatively large flat spring mounted above said valve with its center above the center of said valve and having a plurality of spring tongues in contact with the outlet side of said valve.

10 7. In refrigerating apparatus, the combination of a compressor cylinder, a head for said cylinder, a piston movable in said cylinder for compressing a refrigerant vapor, and an exhaust valve assembly mounted between the head of said cylinder and the compression side of said piston, said assembly comprising a relatively small disc valve, a relatively large flat spring mounted above said valve with its center above the center of said valve and having a plurality of inwardly directed radial tongues in contact with the outlet side of said valve.

15 8. In refrigerating apparatus, the combination of a compressor cylinder, a cylinder head, a piston movable in said cylinder, a removable head for said piston, and a suction valve located within said piston, adjacent said removable head, said removable head having a central protruding portion of reduced area, means between the compression side of said piston and the head of said cylinder forming an exhaust passage into which said central portion of said removable head extends at the end of the compression stroke of said piston, and an exhaust valve mounted between said passage and head of said cylinder.

20 head for said piston, and a suction valve located within said piston, adjacent said head for said piston, said piston having a central opening therein connecting with the suction side of said valve and the suction area of said cylinder during the suction stroke of said piston and said head for said piston having a plurality of circumferentially arranged openings connecting with the discharge side of said valve and the compression side of said cylinder during the compression stroke of said piston.

25 9. In refrigerating apparatus, the combination of a compressor cylinder, a cylinder head, a piston movable in said cylinder, a removable head for said piston, and a suction valve located within said piston, adjacent said removable head, said removable head having a central protruding portion of reduced area, means between the compression side of said piston and the head of said cylinder forming an exhaust passage into which said central portion of said removable head extends at the end of the compression stroke of said piston, and an exhaust valve mounted between said passage and head of said cylinder.

CARL OSCAR BERGSTROM. 25
